US00D378673S

United States Patent [19]

Aochi et al.

[11] **Patent Number:** **Des. 378,673**[45] **Date of Patent:** ****Apr. 1, 1997**

[54] **GRID STRUCTURE FOR SUPPORTING
ANTENNAS AND REFLECTIVE SURFACES
IN EXTRATERRESTRIAL SPACE**

[75] Inventors: **Tak Aochi**, Morgan Hill; **Robert J. Pyle**, Sunnyvale, both of Calif.

[73] Assignee: **Lockheed Missiles and Space Company, Inc.**, Sunnyvale, Calif.

[**] Term: **14 Years**

[21] Appl. No.: **804,342**

[22] Filed: **Nov. 22, 1991**

[52] U.S. Cl. **D12/345**; D14/230

[58] Field of Search D12/345; D25/157, D25/153; 244/159; 428/257, 113; 156/446, 173; D14/230

[57] **CLAIM**

The ornamental design for a grid structure for supporting antennas and reflective surfaces in extraterrestrial space, as shown and described.

DESCRIPTION

FIG. 1 is a top perspective view of a grid structure for supporting antennas and reflective surfaces in extraterrestrial space showing our new design; and, FIG. 2 is a bottom perspective view thereof.
